[57] **CLAIM**

The ornamental design for a shoe upper, as shown and described.

DESCRIPTION

FIG. 1 is a left side elevational view of a shoe upper showing my new design;

FIG. 2 is a right side elevational view thereof;

FIG. 3 is a top plan view thereof;

FIG. 4 is a front elevational view thereof;

FIG. 5 is a rear elevational view thereof.
The broken line showing of an outsole in FIG. 1 is for illustrative purposes only and forms no part of the claimed design.

FIG.1**FIG.2****FIG.3**
